DESIGN FOR A RESERVOIR-CONTAINER

Henry K. Mulford, Philadelphia, Pa., assignor to
The National Drug Company, Philadelphia, Pa.,
a corporation of Pennsylvania

Application June 15, 1936, Serial No. 63,308

Term of patent 14 years

To all whom it may concern:

Be it known that I, Henry K. Mulford, a citizen of the United States, residing in the city and county of Philadelphia and State of Pennsylvania, have invented a new, original, and ornamental Design for Reservoir-Containers, of which the following is a specification, reference being had to the accompanying drawing, forming part thereof.

Fig. 1 is an elevational view of a reservoir-container, showing my new design; and Fig. 2 is a bottom plan view of the same.

I claim:

The ornamental design for a reservoir-container, as shown.

HENRY K. MULFORD.
